Inventor.

UNITED STATES PATENT OFFICE.

ROBERT S. LAWRENCE, OF BUFFALO, NEW YORK.

CARBURETOR.

SPECIFICATION forming part of Letters Patent No. 539,773, dated May 21, 1895.

Application filed September 11, 1894. Serial No. 522,704. (No model.)

To all whom it may concern:

Be it known that I, ROBERT S. LAWRENCE, a citizen of the United States, residing at Buffalo, in the county of Erie and State of New York, have invented a new and useful Improvement in Carburetors, of which the following is a specification.

This invention relates to a carburetor for charging air or gas with hydrocarbon.

10 In carburetors as heretofore constructed a stationary absorbent body was immersed with its lower portion in the hydrocarbon whereby the latter was lifted by capillary attraction into the upper portion of the absorbent body 15 and presented to the current of air or gas in a vaporized state. This construction of a carburetor is suitable only for light highly volatile oils, but for heavy or low grade oils this construction is undesirable because such 20 heavy oils or hydrocarbons are not readily raised by capillary attraction, nor do they vaporize at low temperature.

25 The object of my invention is to produce a carburetor which enables heavy or low grade oils to be employed for carbureting air or gas.

In the accompanying drawings, consisting of two sheets, Figure 1 is a sectional perspective view showing my improved carburetor used in connection with a domestic gas plant. 30 Fig. 2 is a longitudinal sectional elevation of my improved carburetor. Fig. 3 is a horizontal section in line 3 3, Fig. 2. Fig. 4 is a vertical transverse section of the same in line 4 4, Fig. 2. Fig. 5 is a fragmentary section, on an 35 enlarged scale, of the non-conducting filling or insulation.

Like letters of reference refer to like parts in the several figures.

40 A represents a rectangular casing made of copper, zinc, leaded iron, or any other non-corroding material and located in the basement of a building, as shown in Fig. 1, or in any other suitable place. This case is provided with a vertical transverse partition *a* extending 45 from the top to the bottom and from one side to the other of the casing, thereby forming a chamber in the front portion of the casing in which the air or gas enriching devices are arranged.

50 B represents a horizontal diaphragm arranged in the rear portion of the casing about midway of its height and extending length-

wise from the partition *a* to the rear wall and transversely from one longitudinal side to the other of the casing. The chamber *b* below 55 the diaphragm serves as a reservoir in which the carbureting oil is stored. This reservoir is provided with a filling pipe *c* opening into the lower portion of the reservoir and a vent pipe *c'* opening into the upper portion of the 60 reservoir. The inlet of the filler pipe is adapted to be coupled with the oil space of an oil supply tank while the vent pipe is adapted to be connected with the space in the tank above the oil. As the oil flows from the tank into 65 the reservoir a proportionate amount of the gas in the upper portion of the latter escapes into the tank, thereby enabling the reservoir to be filled with oil without permitting any 70 gas to escape into the surrounding atmosphere. The filler and vent pipes extend with their outer ends above the highest level of the oil in the reservoir and are provided with cocks *c* *c'* respectively for shutting off these pipes.

75 D represents a vertical test pipe whereby the amount of oil in the reservoir may be determined. This pipe communicates at its lower end with the lower portion of the oil space, preferably by connecting it with the 80 lower portion of the filler pipe, while its upper end extends above the highest level of the oil and is provided with a screw cap *d* for closing the same. When it is desired to determine the amount of oil in the reservoir the 85 cap *d* is removed and a glass test tube is inserted partially filled with oil and removed for examination, in the usual manner.

E represents an imperforate cylindrical shell arranged transversely in the space between the front wall and the partition *a* of the casing and separated at its ends from the adjacent longitudinal walls of the casing by an inlet chamber *e* and an outlet chamber *e'*, respectively. To secure rigidity the shell is 90 secured directly by soldering at the points where it bears against the casing and between said points it is connected with the casing by braces *e*². The ends of the shell are connected by plates *e*³ with the adjacent portions of the 95 casing and the partition, so as to separate the spaces between the shell and the casing and partition from the inlet and outlet chambers and convert these spaces into dead air cham- 100

bers. Air or gas is introduced into the inlet chamber *e* by a main supply pipe *F* having a cock *f*. The lower portion of the partition is provided between the reservoir and the outlet chamber with a number of openings *g* which permit the oil in the reservoir to flow into the outlet chamber, shell and inlet chamber, wherein it assumes the same level as in the reservoir.

Within the cylindrical shell is fitted an enriching drum or cylinder which becomes saturated with oil and through which the air or gas passes for enriching the same. This drum is constructed as follows:

15 *H* represents a transverse shaft arranged axially in the cylindrical shell and journaled in bearings *h h'* arranged on the longitudinal walls of the casing. This shaft is provided within the shell, near opposite ends thereof, 20 with two open heads or spider wheels *I I* which are connected with each other near their periphery by tie rods *i*.

J represents a perforated shell or cylinder fitting within the outer or imperforate shell 25 and secured with its ends to the periphery of the spider wheels. The perforated shell is connected between the spider wheels with the shaft by a number of perforate radial plates *j* which extend preferably the full length of 30 the perforated cylinder.

k represents perforated heads secured to the outer sides of the spider wheels. The spaces between the perforated shell, the perforated heads and the perforated radial plates are 35 filled with wood fiber or some other suitable porous or absorbent material. The fiber in the lower portion of the drum is immersed in the body of oil and becomes heavily saturated therewith while the upper portion, which is 40 above the level of the oil, becomes only partially saturated by capillary attraction.

The gas or air which is introduced by the supply pipe into the inlet chamber passes from the latter through the upper portion of 45 the enriching drum into the outlet chamber. During its passage through the drum the air or gas absorbs the particles of hydrocarbon which are held in suspension in a finely divided state by the fiber and becomes enriched 50 thereby.

In order to prevent the gas or air from passing between the outer imperforate shell and the inner perforate cylinder, a packing *l* of cloth or other suitable material is interposed 55 between these parts and preferably secured to the inner cylinder.

When a light or highly volatile oil is employed the capillary attraction, unless retarded by low temperature, is powerful 60 enough to lift the oil into the upper portion of the drum and saturate the same sufficiently to enrich the gas or air which passes through the drum.

Heavy or low grade oils are less volatile 65 and do not yield as readily to the influence of capillary attraction and it is therefore necessary to raise the heavy oils into the

path of the air or gas by mechanical means in order to supply the air or gas with a sufficient amount of hydrocarbon. This is accomplished by turning the drum until the lower submerged portion of the drum is raised into the path of the air or gas and the upper portion of the drum is submerged in the oil. By thus turning the drum a replenished and newly charged portion of the drum is presented to the current of air, while the used or dry portion is being recharged. The drum may be turned either intermittently or continuously. As represented in Fig. 1 of 80 the drawings, one end of the shaft projects outside of the casing and is provided with a pulley *m* and the latter is connected by a belt *m'* with a hand wheel *m²* which latter is suitably mounted in one of the rooms over the 85 basement. When a richer gas or brighter light is desired the drum can be rotated by simply turning the hand wheel. Instead of turning the drum by hand the same may be turned by means of a spring, clock work, 90 water motor or electric motor.

The rotary enriching drum forms a mechanical elevating device whereby the liquid hydrocarbon is elevated from the liquid space into the air or gas passage and presented to 95 the passing air or gas for absorption.

In order to prevent the gas from leaking past the bearing *h* the outer side of the casing is provided around the shaft with a receptacle *n* which is filled with water or glycerine and serves as a seal to prevent leakage past this bearing.

As represented in Fig. 1, my apparatus is arranged for carbureting air and in this arrangement an air blower or forcing device *O* 105 of any suitable construction is employed for supplying the necessary air. The blower is provided with an inlet pipe *o'* which opens into the outer atmosphere while the outlet of the blower is connected with the inlet pipe *F* 110 of the carbureter. Instead of carbureting air the apparatus may be used for enriching coal gas, water gas, hydrogen, marsh gas or natural gas. After the air or gas has been carbureted it is then thoroughly mixed, then 115 stripped of its surplus oil and then atomized by the following means:

P represents an internal jacket of the same material as the casing, which lines all the sides of the space between the diaphragm 120 and the top of the casing except the side facing the enriching drum. In order to maintain a low temperature within the jacket a non-conducting filling *Q* is placed between the jacket and the adjacent parts of the casing and the diaphragm. This filling consists 125 preferably of two layers of asbestos *q* and a layer of wire gauze or perforated sheet metal *q'* arranged between the layers of asbestos, as represented in Fig. 5. The inner perforated layer forms numerous small air chambers which check the passage of heat into the interior of the jacket and this in addition to the non-conducting property of the asbestos 130

sheets renders the filling practically imper-
vious to heat.

The interior of the jacket is divided by
two vertical partitions R R' into a mixing
chamber S arranged next to the enriching
device, a stripping chamber T arranged in
rear of the mixing chamber and an atomizing
or attrition chamber U arranged in rear
of the stripping chamber. The mixing cham-
ber is filled with wood fiber which is prevented
from packing too solidly in the chamber by
means of vertical retaining plates s having
numerous perforations in which the wood
fiber catches and by which it is sustained.
15 One end of the mixing chamber is connected
near its top with the upper portion of the
outlet chamber e' by means of perforations
s' formed in the partition a. The lower por-
tion of the mixing chamber is connected at
20 its opposite end with one end of the stripping
chamber by means of openings r formed in
the partition R. The enriched gas enters the
openings s' and passes through the body of
wood fiber in the mixing chamber to the out-
25 let r thereof, whereby the air or gas is thor-
oughly mixed with the hydrocarbon which it
has abstracted.

The stripping chamber is filled with a mix-
ture of asbestos wool and wood fibre which
30 mixture is prevented from packing in said
chamber by means of vertical perforated
plates t similar to the plates s in the mixing
chamber. The diaphragm R' is provided
near its top with an outlet opening r' for the
35 stripping chamber, which outlet is arranged
on the end of the stripping chamber opposite
to that on which the inlet of said chamber is
located. As the mixed air or gas and hydro-
carbon pass through the stripping chamber
40 the fibrous mixture therein strips the air or
gas of its surplus hydrocarbon owing to the
low temperature of the chamber and the ab-
sorbent property of this mixture. The inlet
and outlet openings of the mixing and strip-
45 ping chambers are provided with perforated
guards v which prevent these openings from
being choked by the fibrous material in said
chambers.

W represents an atomizing or attrition pipe
50 arranged in the upper portion of the atomizing
chamber and communicating with the
outlet of the stripping chamber. This pipe
has the form of an open rectangular frame
55 spray openings, the openings on one side of
the frame facing those of the opposite side.
The enriched gas or air passing from the
stripping chamber into the atomizing pipe
issues from the spray openings thereof which
60 causes the sprays from opposite sides to im-
pinging against each other, thereby atomizing
or breaking up the gas or air into minute
molecules, which condition is best suited for
perfect combustion upon igniting the same.
65 The atomization of the enriched gas or air is
promoted by low temperature and for this
purpose the lower portion of the atomizing

chamber is filled with sticks of charcoal or
other carbonaceous material which tends to
maintain a uniform low temperature. The 70
under side of the atomizing pipe is provided
with a number of drip openings w which per-
mit any condensed hydrocarbon to escape
from said pipe into the atomizing chamber.

X represents a covering of cloth or similar 75
absorbent material which rests upon the bot-
tom of the jacket and extends underneath
the partitions R R' and retaining plates s t.
This cloth absorbs the hydrocarbon which is
separated from the air or gas in the mixing, 80
stripping and atomizing chambers and con-
ducts the same to a return opening y which
extends through the bottom of the stripping
chamber, the jacket, filling and diaphragm
and whereby the separated hydrocarbon is 85
carried back into the reservoir. The inlet of
return opening y is provided with a perfo-
rated guard y' which prevents said opening
from being choked by the packing in the
stripping chamber. 90

z represents the outlet pipe whereby the
carbureted gas or air is drawn off from the
atomizing chamber and conducted to the
place of consumption. This outlet pipe is
provided with a cock z' for regulating the 95
escape of the carbureted air or gas.

z² is a cross pipe connecting the inlet pipe
F with the outlet pipe z and provided with a
cock z³. When the carburetor is in working
order the cock of the cross pipe is closed and 100
the cocks of the inlet and outlet pipe are
open so that the air or gas is compelled to
pass through the carburetor. If the carbure-
tor should get out of order, or it is desired
105 for any other reason, to cut the carburetor
out, this is readily accomplished by closing
the cocks of the inlet and outlet pipes and
opening the cock z³, thereby permitting the
gas to pass directly from the inlet to the out-
let pipes. 110

z⁴ is a branch pipe connecting the cross
pipe with the mixing chamber and provided
with a cock z⁵. When it is desired to pro-
duce a very rich gas for illuminating pur-
poses the cock of the branch pipe is closed, 115
which compels all of the air or gas to pass
through the enriching drum but when the
gas is to be used for heating purposes the cock
of the inlet pipe is partly closed so as to re-
duce the amount of air or gas passing through 120
the enriching drum and the cock of the branch
pipe is opened to permit a portion of the air
or gas to pass directly into the mixing cham-
ber, thereby reducing the richness of the gas
and its illuminating qualities without reduc- 125
ing its heating qualities.

By my improved carburetor the cost of pro-
ducing carbureted air or gas is reduced con-
siderably owing to the comparatively small
cost of low grade hydrocarbons which can be 130
used instead of high grade hydrocarbons. If
desired the casing may be entirely covered
by a jacket of water, asbestos, cement, char-
coal or other suitable non-conductor, whereby

the machine is protected against the extremes of heat and cold.

During long continued service at full capacity the capillary attraction is retarded and eventually arrested entirely in carburetors as heretofore constructed owing to the extremely low temperature produced by vaporization. This difficulty is overcome by my improved carburetor, in which the elevation of the hydrocarbon of any grade does not depend upon capillary attraction, but is effected by mechanical means.

I claim as my invention—

1. In a carburetor, the combination with the inlet chamber, the outlet chamber and the cylindrical imperforate shell connecting said chambers, of a rotary perforated cylinder arranged in said shell and filled with an absorbent material and a packing arranged between the shell and the cylinder, substantially as set forth.

2. In a carburetor, the combination with the casing, of a vertical partition arranged in the casing and forming an enriching chamber in the front end of the casing, a diaphragm arranged in the rear portion of the casing and forming a reservoir below the diaphragm which communicates with the lower portion

of the enriching chamber, a mixing chamber formed in the casing above the diaphragm and communicating with the upper portion of the enriching chamber, a stripping chamber arranged above the diaphragm and communicating with the mixing chamber and an atomizing chamber arranged above the diaphragm and communicating with the stripping chamber, substantially as set forth.

3. In a carburetor, the combination with the enriching chamber, the mixing and purifying chambers receiving the carbureted fluid therefrom, and the atomizing chamber, of an atomizing pipe arranged in said atomizing chamber and having the form of an open frame provided on its inner sides with opposing rows of spray openings, said pipe receiving the carbureted fluid from the mixing and purifying chambers and delivering it through its spray openings into the atomizing chamber, substantially as set forth.

Witness my hand this 8th day of September, 1894.

ROBERT S. LAWRENCE.
